UNITED STATES PATENT OFFICE.

HENRY W. JUSTUS, OF NAPANOCH, NEW YORK.

STEAM TRAP.

Application filed April 28, 1927. Serial No. 187,241.

This invention relates to valve controlling means which is especially designed for a steam trap, but which, of course, can be used for other purposes, such as boiler feeds, 5 damper regulators, pump governors, etc.

The general object of the invention is to provide an assembly of diaphragms and valves actuated by fluid pressure for automatically controlling the main valve through 10 means of a float or other device.

This invention also consists in certain other features of construction and in the combination and arrangement of the several parts, to be hereinafter fully described, illustrated in the accompanying drawings and 15 specifically pointed out in the appended claims.

In describing my invention in detail, reference will be had to the accompanying 20 drawings wherein like characters denote like or corresponding parts throughout the several views, and in which:—

Figure 1 is an elevation with parts in section, showing the invention applied to a 25 steam trap.

Figure 2 is an enlarged sectional view through a portion of the trap, the controlling device and the float operated valve.

In these views, 1 indicates the casing of 30 the trap which is so placed that it will receive the water of condensation from a steam system, the inlet pipe being shown at 2, and a baffle 3 having holes 3' therein serves the purpose of checking the velocity of the water 35 rushing in through the inlet pipe 2 so that this baffle prevents the rush of water from interfering with the proper action of the float. The holes 3' near its bottom act to equalize the level in the two compartments 40 and keeps the water comparatively quiet. The outlet pipe is shown at 4, and this pipe passes through the top of the casing and extends to a point close to the bottom of the casing. A valve casing 5 is connected with 45 the upper end of the pipe 4 and has a discharge pipe 6 connected therewith. The valve 7 in this casing has its stem extending into a diaphragm casing 8, the diaphragm 9 resting upon a head 10 on the stem. A 50 spring 11 on said stem normally holds the valve in open position.

A casing 12 is in communication with the top of the trap 1 and a pipe 13 connects the top of the casing 12 with the diaphragm casing 8, an automatic air valve 14 being arranged above the point of connection of the

pipe 13 with the casing 8. A valve seat carrying member 15 is arranged in the casing 12, the seat being adapted to be engaged by a valve 16 which is actuated through 60 means of a float 17 in the trap, these parts being so arranged that when the float is raised by the accumulation of water in the trap, the valve 16 will be pressed against the seat and thus prevent the escape of steam 65 from the trap.

A sectional casing 18 is formed with the diaphragm chambers 19 and 20, one at each end thereof, and with a central chamber 21 which is in communication with both diaphragm chambers. A valve 22 controls the communication between the lower diaphragm chamber and the central chamber and the stems 23 of this valve have their heads 24 engaging the diaphragms 25 and 25' in said chambers. The lower chamber, below the diaphragm therein, is in communication with the trap and a pipe 26 connects the top part of the top chamber with the passage 27 which connects the central chamber 21 with the lower diaphragm chamber, and this passage is connected with the valve casing 12 by a pipe 28. The central chamber is connected by a pipe 29 with the valve casing 5 above the valve therein. 80

Assuming that the trap is empty or practically so, and the float is in lowered position, steam will pass through the casing 12 and pipe 13 into the diaphragm casing 8 and depress the diaphragm therein and thus hold the valve 7 to its seat. Some of the steam will also enter the upper parts of the two diaphragm chambers in casing 18, and this pressure in the lower chamber will balance the pressure on the diaphragm therein, 90 caused by the steam entering this diaphragm chamber directly from the trap, which is a permanent pressure, and thus this diaphragm in the lower chamber will be held in its neutral position. The pressure 100 in the upper chamber will depress the diaphragm therein and thus the valve 22 will be held on its seat. Thus all valves will be held closed, except the float operated valve. As the water of condensation from 105 the system gradually fills the trap, the float will raise until the valve 16 is closed, and this will cause a drop in pressure in the upper portions of the diaphragm chambers in casing 18 and also in the diaphragm 110 chamber 8. This will permit the steam pressure in the trap to overbalance the lower

diaphragm in chamber 18, which will raise valve 22 off its seat so that steam can pass from the upper chamber in casing 18 through pipe 26, passage 27, into chamber 21, from which it will pass through the pipe 29 into the casing 5, while the steam in casing 8 will pass through pipe 13, casing 12, pipe 28 into chamber 27 and then through passage 21 and pipe 29 to the casing 5. Thus the pressure is relieved in diaphragm casing 8 so that the spring 11 can open the valve 7, which will permit the steam pressure, acting on the water in the trap, to force the water through pipe 4, valve casing 5 and through discharge pipe 6. As the float drops, due to the discharge of water from the trap, the valve 16 will again be moved from off its seat so that steam will again pass into the diaphragm chambers, causing the valves 7 and 22 to close, which will prevent the escape of steam through the exhaust. Thus the device will automatically operate to keep the trap free of water and, as before stated, while the device is primarily designed to control the discharge valve of a steam trap, it may be used for automatically closing and opening a valve of a boiler feed, damper regulator, pump governor, etc.

30 It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. In combination with a steam trap and its controlling valve, means for normally holding the valve in open position, a diaphragm chamber associated with the valve, a diaphragm in the chamber, means for supplying steam to the diaphragm chamber from the trap to cause the diaphragm to close the valve, a float operated valve for controlling the supply of steam to the diaphragm chamber, a casing having an exhaust chamber and upper and lower diaphragm chambers therein and a passage connecting the exhaust chamber with the lower diaphragm chamber, a diaphragm in each diaphragm chamber, the lower chamber having its lower part in communication with the trap, means for placing the upper part of the top diaphragm chamber in communication with the passage, a valve for controlling communication between the passage and the exhaust chamber, stems on the

valve engaging the upper and lower diaphragms and means for placing the passage in communication with the means for connecting the trap with the main diaphragm chamber above the float operated valve.

2. In combination with a steam trap, a valve for controlling the passage thereof, a spring for normally holding the valve open, a diaphragm chamber associated with the valve, a diaphragm therein, a valve casing on the top of the trap, a pipe connecting the same with the diaphragm chamber so that steam from the trap will enter the chamber to cause the diaphragm therein to force the valve upon its seat, a valve in the casing, a float for closing the valve when the water of condensation rises in the trap, a diaphragm casing formed with upper and lower diaphragm chambers and a central chamber with a passage connecting the central chamber with the lower diaphragm chamber, the bottom part of the lower chamber being in communication with the trap, diaphragms in the diaphragm chambers, a valve for controlling communication between the passage and the central chamber, stems on said valve engaging the diaphragms, a pipe connecting the passage with the top part of the top chamber, a pipe connecting the passage with the casing of the float operated valve and a discharge pipe connecting the central chamber with the casing of the main valve.

3. In combination with a control valve, a supply of compressed fluid, means for operating the valve by some of the fluid from said supply, an automatic valve for controlling the flow of fluid from the supply to the valve operating means, a casing having an exhaust chamber, upper and lower diaphragm chambers therein and a passage connecting the exhaust chamber with the lower diaphragm chamber, a diaphragm in each diaphragm chamber, the lower chamber having its lower part in communication with the supply, means for placing the upper part of the top diaphragm chamber in communication with the passage, a valve for controlling communication between the passage and the exhaust chamber, stems on the valve engaging the upper and lower diaphragms, and means for connecting the passage with the supply, such connecting means being controlled by the automatic means before mentioned.

In testimony whereof I affix my signature.

HENRY W. JUSTUS.
